TOOL FOR REMOVING FEEDERS OR SPRUES FROM INGOTS AND THE LIKE

William W. Grossett, Munhall, Pa., assignor to
Carnegie-Illinois Steel Corporation, a corpora-
tion of New Jersey

Application December 9, 1941, Serial No. 422,302

3 Claims. (Cl. 294—82)

This invention relates to a tool and, particularly, to an improved tool for removing feeders or sprues from castings, such as ingots and the like.

In the steel industry it is common practice, in casting ingots, to pour the molten steel into a series of ingot molds at one time. That is, the bottoms of the molds are interconnected by means of a runner with the molten steel poured into the runner, from which the molten steel passes into the ingot molds connected thereto at the bottom thereof. Such a method of pouring is generally known as "bottom pouring" and is a desirable method, particularly for pouring alloy steel ingots. After the pouring of the molten steel into the runner and the molds have been filled and the steel has solidified therein, the molds are lifted or stripped from the ingots. After such stripping operation, it will be seen that the ingots are connected together by a series of feeders or sprues formed by the solidification of the excess metal in the runner. It is, of course, necessary that the connecting feeders or sprues be broken and removed from the bottom of the ingots, so as to provide a plurality of individual ingots, before the ingots can be charged into furnaces for preheating for further processing, or be moved to another position within the plant.

Heretofore, it was the usual practice to break these feeders or sprues from the molds by means of a wire rope sling wrapped or looped around the feeders or sprues, with the sling attached to the hook of an overhead crane. The feeders so connected to the crane hook were then broken from the ingots by swinging the ingots by means of the crane against a pile of ingots, condemned molds, or any other suitable solid mass of material, until the feeders or sprues were broken from the ingots. The use of a wire rope sling has proved unsatisfactory for the reason that the sling is rapidly heated, and is crushed and kinked so severely that it has to be replaced after it is used but once, thereby necessitating frequent replacement. Furthermore, the sling did not grasp the feeders or sprues very securely and oftentimes the sling would tend to slip therealong and therefrom. Accordingly, the present invention relates to an improved tool for grasping and removing such feeders or sprues from ingots and the like whereby the above named disadvantages are eliminated.

It is one of the objects of the present invention to provide an improved tool or device for breaking feeders or sprues from ingots and the like which is simple and inexpensive in its construction and,

at the same time, a tool which is efficient and effective in its use.

It is another object of this invention to provide an improved tool or device for breaking feeders or sprues from ingots and the like which firmly grips the feeders or sprues and which may be locked securely in position thereon, thereby eliminating the danger of having the tool accidentally slip therefrom.

It is a further object of this invention to provide an improved tool or device for breaking feeders or sprues from ingots and the like which is flexible and adaptable for use with feeders or sprues which vary in diameter over a relatively wide range and which have an adjustable locking means arranged therewith.

Various other objects and advantages of this invention will become more apparent during the course of the following specification and will be particularly pointed out in the appended claims.

In the accompanying drawing there is shown, for the purpose of illustration, one embodiment which my invention may assume in practice.

In the drawing:

Figure 1 is a front elevational view of the improved tool of my invention;

Figure 2 is a side elevational view thereof;

Figure 3 is a side elevational view similar to Figure 2, showing a complete assembly of the tool, together with the workpiece;

Figure 4 is a plan view of the pin member incorporated with my improved tool; and

Figure 5 is an end view of the pin member shown in Figure 4.

Referring more particularly to the drawing, the improved tool of my invention consists of a body member 2 having a hook-shaped portion 3 arranged on the lower end thereof. The hook-shaped portion 3 consists preferably of a shank 4, a jaw portion 5, and a point 6. The jaw portion 5 is preferably of such width as to provide a relatively broad-faced surface 7 on the inner side of the jaw 5 opposite the throat portion 8. There is arranged, through the hook-shaped portion 3, a pair of aligned openings or holes 9 with one of the holes arranged in the shank portion 4 and the other hole arranged directly opposite thereto in the point 6. The holes 9 are preferably elliptical or oval in shape and are spaced from the inner broad surface of the jaw 5.

There is provided a wedge, preferably in the form of a tapered pin member 10, which is adapted to be disposed through the pair of aligned holes 9 in the hook-shaped portion 3. The pin member 10 also has preferably an ellip-

tical- or oval-shaped cross-section and the holes 9 are preferably substantially larger than the diameter of the pin 10, for a purpose hereinafter to be described. One end of the pin member 10 is connected to the body member 2, preferably on the back side thereof as at 13, by means of a flexible member, such as a chain 12. It is the purpose of the chain to keep the pin member 10 attached to the body member at all times so that the pin is ready for use and so as to prevent the pin from becoming lost or mislaid.

There is also arranged on the back side of the body member 2, preferably toward the upper end thereof, a handle portion 14, preferably in the form of a loop, for manipulating the tool in a manner hereinafter to be described. On the extreme upper end of the body member, directly above the handle portion 14, there is arranged an eye portion 15 for receiving a pin or bolt 16. There is also attached to the bolt 16 preferably a clevis member 17 for the purpose of attaching the tool to the hook of a chain or similar apparatus. That is, the clevis 17 is pivotally attached to the eye portion 15 of the body member by means of the bolt 16.

The improved tool of my invention is used in the following manner. After the ingots or castings have been poured and the metal has solidified therein, and the molds stripped from the ingots, the tool of the present invention is positioned around the feeder or sprue of the ingots by means of the handle 14 carried thereby, with the feeder or sprue being disposed in the throat portion 8 of the tool and against the inner broad-faced surface 7 of the jaw portion 5. The pin member 10 is then inserted in the aligned holes 9, with the pin straddling or bridging the feeder or sprue, as shown in Figure 3 of the drawing, so as to provide a wedging action against the top of the feeder or sprue. It will be understood that the pin is driven into place in the holes 9 so that the feeder or sprue is securely positioned against the broad-faced surface 7 of the jaw 5, with the lower side of the pin bearing against the top of the feeder or sprue. It will be seen that the feeder or sprue is then securely and firmly held in position in the hook-shaped portion of the tool. By providing such a construction, it will be seen that the pin 10 is held against the feeder or sprue with any desired pressure, depending on how far the pin is driven into the holes.

The clevis 17 is then attached or hooked over the end of the hook of an overhead crane or similar apparatus and the feeder, being firmly gripped by the tool, is then broken from the ingot by swinging the same against another pile of ingots, condemned molds, or other solid mass of material. After the feeder or sprue has been broken from the ingot or casting, the pin 10 is driven from position in the aligned holes 9 and

the feeder or sprue removed from the hook-shaped portion of the tool.

It will be seen that, due to the fact that the holes 9 are substantially larger than the tapered pin 10, the tool of the present invention can be used for removing various sized feeders or sprues from castings or ingots. It will be understood that the pair of aligned holes 9, together with the pin member 10 which cooperates therewith, are elliptical- or oval-shaped to maintain the pin in substantially a vertical plane at all times. That is, the elliptical cross-section of the holes and pin will prevent the pin from rolling in the holes when the tool is in use, which is a decided advantage.

As a result of my invention, it will be seen that there is provided a tool for removing feeders or sprues from ingots and castings which is convenient and safe in its use and, at the same time, 20 a tool which firmly grips the object or feeder so that the same is securely held in engagement with the tool, regardless of the direction of pull by the tool.

While I have shown and described one specific 25 embodiment of my invention, it will be understood that this embodiment is merely for the purpose of illustration and description and that various other forms may be devised within the scope of my invention, as defined in the appended claims.

I claim:

1. A tool for removing feeders or sprues from ingots and the like comprising a body member having a relatively broad-faced hook-shaped portion arranged on the lower end thereof, a removable tapered cylindrical pin member, said body member having a pair of aligned elliptical-shaped holes arranged transversely through the hook-shaped portion thereof at a spaced distance 35 from the bottom of said hook-shaped portion in which holes the tapered pin is adapted to be adjustably disposed for retaining the hook-shaped portion in engagement with the feeder or sprue to be grasped thereby with each of said 40 holes having a diameter substantially larger than the diameter of said pin, and means arranged on the upper end of said body member for connecting the tool to a manipulating means.

2. A tool for removing feeders or sprues from 50 ingots and the like, as defined in claim 1, including a handle member arranged on the back side of said body member for manipulating the same together with the hook-shaped portion carried thereby.

3. A tool for removing feeders or sprues from 55 ingots and the like, as defined in claim 1, wherein the means for connecting the tool to a manipulating means consists of a clevis member pivotally connected to the body member adjacent the top thereof.

WILLIAM W. GROSSETT.
